UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,554, dated January 7, 1890.

Application filed December 9, 1889. Serial No. 333,155. Term of patent 3½ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design is generally rectangular on the ground plan, the whole being surmounted by a gable roof. One slope of said gable roof extends down to the top of the first story, while the other slope of said roof only extends down to the top of the second story. The front of the residence discloses at one corner a porch A, over which the long slope B of the roof extends. A flight of steps a leads up to this porch. To the right of the flight of steps a is an octagonally-

shaped bay D, shown as forming the base of a tower C. The tower C apparently rises from the roof. At the second story it is octagonally-shaped. At the third or attic story 30 it is provided with a balcony E, the balcony E being surmounted by a conical or octagonally-shaped roof F. Pillars e are represented as forming the supports for the portion of the roof F which extends over the balcony E. At 35 one side of the tower C and rising from the roof is a dormer-window G, provided with a hipped roof. The end of the residence is shown as having a rectangularly-shaped bay H both upon the first and second stories, between the gable of the roof. Extending rearwardly from the main portion of the residence is an extension I, to which a flight of steps J leads.

What I claim is—

The design for the exterior of a residence, substantially as herein shown and described.

WILLIAM K. BENEDICT.
